CLAIM

The ornamental design for a band for a smart watch, as shown and described.

DESCRIPTION

FIG. 1 is a top, left side isometric view of our new design for a band for a smart watch.

FIG. 2 is a bottom left side isometric view of FIG. 1.

FIG. 3 is a top side plan view of FIG. 1.

FIG. 4 is a bottom side plan view of FIG. 1.

FIG. 5 is a left side elevation view of FIG. 1.

FIG. 6 is a right side elevation view of FIG. 1.

FIG. 7 is a front side elevation view of FIG. 1; and,

FIG. 8 is a back side elevation view of FIG. 1.

The broken lines shown in the drawings depict portions of a band for a smart watch that form no part of the claimed design.
